CLAIM

The ornamental design for a golf club iron head, as shown and described.

DESCRIPTION

FIG. 1 is a perspective view of our new design for a golf club iron head, the related environmental structure, such as the outer perimeter and hosel portion, are shown in broken lines throughout the figures and form no part of the claimed design;

FIG. 2 is an elevational view of the design of FIG. 1;

FIG. 3 is a side elevation of the design of FIG. 1, taken along the 3—3 line in FIG. 2;

FIG. 4 is a planar cross-section of the design of FIG. 1, taken along the 4—4 line of FIG. 2;

FIG. 5 is a planar cross-section of the design of FIG. 1, taken along the 5—5 line of FIG. 2; and,

FIG. 6 is a planar cross-section of the design of FIG. 1, taken along the 6—6 line of FIG. 2.
